SOFA-BED.

1,271,725.

Specification of Letters Patent.

Patented July 9, 1918.

Application filed January 11, 1915. Serial No. 1,603.

To all whom it may concern:

Be it known that we, JULIUS KRAMER, JOSEPH UMHOFER, FRANK J. ERAL, and HENRY WILDBERGER, citizens of the United States of America, and residents of Chicago, county of Cook, and State of Illinois, have invented certain new and useful Improvements in Sofa-Beds, of which the following is a specification.

10 This invention relates to sofa beds in which the back is formed with a storage space adapted to receive articles of bedding and particularly that type in which the front portion of the back may be swung forward and downward at the top to give access to the storage space.

Sofa beds have been made heretofore in which the swinging member of the back is connected permanently to the rigid portion 20 by links depending from stationary pivots fixed therein. It is desirable, in order to facilitate packing, shipping, and assembling sofa beds, that a knock-down form of construction be used throughout as far as practicable, and means have been devised heretofore for making the seat demountable with respect to the sofa frame and also means for making the sofa back detachable from the frame ends.

30 The main objects of this invention are to provide an improved form of hollow sofa back having a swinging front portion, and to provide improved means for mounting the swinging portion whereby it shall be readily demountable with respect to the stationary portion or main framework of the back, and whereby in swinging to and from its folded position it shall clear the seat member, especially where the latter is upholstered and projects rearward closely beneath the swinging back; to provide co-acting pivot and slot means of simple character for mounting the swinging back adjacent to its base and adapted to carry the 40 lower portion thereof in such manner that its lower front corner shall clear the seat as the top portion swings forward and downward in opening; and to provide improved stop means for limiting the forward swing 45 of the movable back member.

Illustrative embodiments of this invention, including certain modifications are

shown in the accompanying drawings, in which:

Figure 1 is a fragmentary section of the 55 sofa bed, in its sofa form, on the line A—A of Fig. 2.

Fig. 2 is a vertical cross section on the line B—B of Fig. 1, and shows an end view of the sofa bed with the near end of the 60 frame removed, the swinging back being in its normal position.

Fig. 3 is like Fig. 2 except that the lower portion is broken away and the swinging 65 back is tilted forward.

Fig. 4 is a fragmentary longitudinal section on the line C—C of Fig. 2.

Fig. 5 is a cross-section of the back in its normal position and showing a double slot and stud construction for the mounting 70 plates.

Fig. 6 is similar to Fig. 5 except that the back is swung forward.

Fig. 7 is a front view of the double slotted 75 guide plate of Fig. 6.

Fig. 8 is a section on the line F—F of Fig. 7, showing the form of slots in the plate there shown.

Fig. 9 is a rear or inner side view of the 80 pivot plate of Figs. 5 and 6, in the position of Fig. 3.

Fig. 10 is a plan view of the plate of Fig. 9.

In the construction shown in the drawings, the sofa bed comprises a frame 1, having ends 2 connected by the stationary portion 3 of the back, a seat 4 and a swinging back member 5 formed to serve as a storage receptacle for bedding. Said seat may be of any desired type, preferably rotary, with 85 a foldable bed bottom 6 carried on its under side, substantially as shown in the Harry D. Bartlett Patent No. 1,115,769, dated November 3, 1914.

The swinging back 5 is supported pivotally or substantially so at a point adjacent to its base, and the upper part swings forwardly and downwardly in opening; said back in swinging open is arrested by stop means adjacent to its base; and the back 5 100 is demountable simply by lifting out of its bearings.

Referring to Figs. 2, 3 and 4, the swinging back is supported at each end by a pair of

plates 10 and 11 formed with a slot 12 and pivot 13 respectively, adapted for coaction in swinging the back, plate 10 being fixed to the end of the back 5 and plate 11 to the sofa 5 end 2. Said slot 12 is formed to provide for raising the back 5 somewhat as the top is swung forward, so that the lower front edge 14 of the swinging back shall clear the rear portion of the seat, which is usually formed 10 to project under the normal position of the back. With this object in view, the slot is formed to throw the plate upwardly and forwardly with respect to said pivot 13 in swinging the back forward, said slot as a 15 whole having a forward and upward inclination and preferably being nearly vertical at its lower end and curved forwardly at its upper end, though the precise form of the slot may be varied. An aperture 15 is provided in the lower rim or concave side of 20 said slot for the passage of said pivot into and out of said slot in mounting and demounting said back 5. Said pivot 13 is headed and said slot 12 is correspondingly 25 flanged to retain said pivot. Stop means are provided for arresting the opening or forward swinging of said back 5. In this instance the vertical corner post 17 of the sofa frame is provided with a notch 18 to receive 30 the lower rear corner 19 of the swinging back as it moves upward in opening, said corner sliding into said notch and thereby arresting the swinging. The stop means, if desired, may be made selective, for which 35 purpose a plurality of notches may be provided, as indicated by the dotted line at 22 in Fig. 2, whereby the degree of opening may be adjusted at will. In case a plurality of notches are used, the back may be 40 prevented from engaging the lower notch by lifting somewhat on the back as it swings forward to its widest position.

Referring to Figs. 5, 6, and 7, the back 5 at each end is mounted to swing on a pair of plates 50 and 51 fixed to the adjacent end 2 and back 5 respectively. The coactive support means of each pair of plates comprise two studs or pins 54 and 55, one of which, 54, acts normally as a stationary pivot, and 50 the other moves in an arc concentric therewith, and two guide slots 57 and 58 for said studs respectively, said slots being formed open at one end to facilitate mounting and demounting the back 5. In this instance the 55 studs are both carried by the stationary plate 50 and the slots are both formed in the back plate 51, said slots both terminating at the front edge of said plate 51 where they are open ended.

60 The lower slot 57 turns downward immediately from its opening and terminates as a socket or center bearing for the forward

pivot 54. The upper slot 58 likewise turns downward from its opening for a like distance, and thence turns backward and downward in an arc concentric with the lower end of slot 57, said arc being preferably about 60° corresponding to the angular opening of the back when swung forward. Said slots and studs may be flanged and headed respectively as shown. When the back 5 is swung forward the stud 55 slides in slot 58 and is arrested by the shoulder 60 adjacent to the open end of said slot. The back 5 may be removed when open by lifting the same so as 75 to cause the studs 54 and 55 to slide upward and forward out of their slots.

The operation of the device of this invention is as follows: The swinging back is opened by grasping the upper edge and pulling the same forward until said back is arrested by the stop provided therefor. When the device is in its open position it is so held by gravity, and when closed gravity likewise tends to so hold it. Said swinging back is 85 closed merely by lifting on the forward or upper edge and swinging it back to its normal position. Said swinging back may be operated when the seat is in either its normal sofa position or in its inverted position.

It is to be understood that some of the details shown may be altered or omitted without departing from the spirit of this invention as defined by the following claim.

We claim:

In a sofa bed, a frame having ends spaced apart and a swinging hollow back carried pivotally by and between said ends, in combination with mounting means at each end of said back comprising a pair of plates, one 100 fixed to the adjacent end of the frame and the other fixed to the adjacent end of said back adjacent to its bottom, the movable plate having a pair of pivot-like studs spaced apart and facing outward, and the stationary plate 105 having a pair of slots therein extending forward one over the other and each open ended at its front end, the lower slot turning downward and terminating, and the upper slot turning down and thence lying in an 110 arc concentric with the inner end of the lower slot and spaced therefrom according to the spacing of said studs, said studs coacting with said slots respectively.

Signed at Chicago this 8th day of January, 1915.
